UNITED STATES PATENT OFFICE.

WILLIAM HENRY MEYER, OF AFTON, MINNESOTA.

WASHING-MACHINE.

SPECIFICATION forming part of Letters Patent No. 593,596, dated November 16, 1897.

Application filed December 29, 1896. Serial No. 617,356. (No model.)

To all whom it may concern:

Be it known that I, WILLIAM HENRY MEYER, a citizen of the United States, residing at Afton, in the county of Washington 5 and State of Minnesota, have invented certain new and useful Improvements in Washing-Machines, of which the following is a specification.

This invention relates to washing-machines 10 of that class employing a swinging or oscillating rubber mounted within a tub-body; and the object of the same is to effect certain improvements on Patent No. 252,493, issued to me on January 17, 1882.

15 To this end the invention consists in the specific details hereinafter described and distinguished from that which was covered by my former patent, and the whole being shown in the accompanying drawings, wherein—

20 Figure 1 is an end elevation of the machine partly broken away, with the rubber swung out of the tub and inverted. Fig. 2 is a perspective view and showing the parts in position.

25 The same letters of reference are employed, as nearly as possible, that occurred in my former patent and reference-numerals are used for parts which were not shown therein.

Referring to the drawings, the letter A designates a semicylindrical tub mounted on supporting-legs B and having ribs *a* secured along its bottom on the interior, as shown in dotted lines in Fig. 1, while the upper edges of its ends are notched, as at 1, and the top of 35 this tub is closed by a removable cover (not shown) and forming no part of the present invention.

30 C are two segmental plates standing within the tub and having their curved edges substantially parallel with the curvature of its bottom, such edges being connected by longitudinal ribs *b*, connecting the two segments. The latter form a fourth or fifth of a complete circle, and at the ends of the series of ribs *b* 40 are cross-bars², standing on edge with respect to the ribs *b* and having curved outer faces 3. I have found that unless these cross-bars are employed the clothes being washed are quite liable to form a bundle, which wedges during 45 the movements of the machine into the space between the rubber and the ribbed bottom of the tub, and hence I consider the use of such

cross-bars of the specific shape shown in dotted lines to be an advantage.

D is a shaft extending longitudinally across 55 the tub and standing within the notches 1, while one end of this shaft is upturned to form a handle E, as illustrated. At points just above the plates C C this shaft is flattened at top and bottom, as at 5, while 6 6 are 60 clip-plates standing within the upper flattened portions, and 7 7 are screws passing through the ends of these plates astride the shaft and down into the upper ends of the segmental plates C C, as best seen in Fig. 65 2. By such means the segmental plates are always held at a proper angle to the shaft D, unless it is desired to remove them for cleansing or repair, while the handle E is integral with the shaft, and hence stands at a permanent angle thereto, and this I consider an improvement over the set-screws formerly employed, for the latter were liable to become loose or rusted—hence being too free or too tight, as the case might be.

75 The letters F F designate two levers pivoted, as at *c*, to the outside of the tub-body A upon either side and at one side of the notches, and in their outer ends are bearings in which the extremities of the shaft D are journaled 80 at points outside the tub-body, and hence outside the points of connection of the segments C therewith, one journal being also inside the handle E. To the inner ends of these levers and on the side opposite the journals of the 85 shaft D are connected the extremities of a U-shaped handle G, standing upright when the shaft is within the notches, and which handle may have at suitable point or points on its body a handpiece or handpieces 10 for 90 a purpose to appear below.

11 are brackets secured to the ends of the tub-body at the other side of the notches, and attached thereto is one of the extremities of V-shaped springs 12, whose other extremities 95 bear upward beneath the outer ends of the levers F, thus tending to raise the shaft D and its rubber off the clothes within the tub.

All parts of this machine are of the preferred materials and construction, except as 100 herein described, and considerable change in the specific details may be made without departing from the principle of my invention.

The operation of my improved washing-

machine is as follows: By drawing outward and downward the handle E and handpiece 10 until the handle strikes a rung connecting the legs of the body, as seen in Fig. 1, the shaft 5 D is elevated so as to raise the entire rubber C^b out of the tub-body, as seen in Fig. 1. The clothes or articles to be washed are then inserted, together with the proper amount of suds and water, and the rubber brought back 10 to operative position. In the act of swinging the rubber back to place the shaft D of course enters the notches 1 in the tub-body. Meanwhile the free or outer ends of the levers F strike and rest upon the tips of the springs 15 12, which are conveniently placed at the opposite sides of the notches from the pivots C, and the springs support such ends and the shaft D at a proper elevation to hold the ribs b at an average distance above the ribs a, that 20 will admit the clothes between the two ribbed surfaces. The handle E is then reciprocated in a manner which will be clear, and its movement causes the rubber to move back and forth over and slightly above the corrugated 25 bottom of the tub, the handpiece 10, which stands in convenient position, being meanwhile pressed by the other hand of the operator in proper direction to cause the rubber to bear downward upon the clothes and press 30 them against the ribs a on the inner face of the bottom of the tub-body. The presence of the cross-bars 2, however, holds the clothes approximately flat, so that they receive the best washing possible and prevent the clothes 35 from lumping or rolling into a bundle, the undesirable results of which are that the exterior surfaces of such bundle only are washed, while the center remains dirty. The springs 10 prevent the entire weight of the shaft and rubber 40 from bearing the clothes too firmly downward upon the ribs a of the tub, and yet their pressure may be overcome partially or entirely by bearing on the handpieces 10 of the handle G. After the clothes are washed the rubber is

swung out as before and the cleansed clothing 45 removed and new articles substituted if the operation is to be continued. If the rubber is to be removed for cleansing or repair, the screws 7 are withdrawn until the clip-plates 6 can be removed, when the segments C can be 50 easily detached from the shaft D; but when these segments are again connected therewith they will necessarily stand at the same angle to the shaft by reason of the flattened portions 55 thereof.

I might add that the shaft D is preferably of metal, as may also be the handle G, while the remaining parts are preferably of wood. Any additions that may occur to the manufacturer may be made without departing from 60 my invention in the least.

What is claimed as new is—

In a washing-machine, the combination with a tub-body ribbed on its interior and notched at the upper edges of its ends, a shaft standing within said notches, an upright handle secured to said shaft, and segments pendent from the shaft and having connecting-ribs parallel with those of the body; of levers pivoted to the tub-body at one side of the notches 70 therein, bearings in the outer ends of the levers supporting the extremities of the shaft, a handle connecting the inner ends of the levers and leading over the body, brackets secured to the ends of the latter at the opposite 75 side of its notches, and V-shaped springs each secured at one end to one of the brackets and having its other end sustaining the outer end of one lever and hence one extremity of the shaft, substantially as described.

In testimony whereof I have hereunto set my hand in presence of two subscribing witnesses.

WILLIAM HENRY MEYER.
